GEORGE W. WARREN, OF ALMA, NEW YORK.

Letters Patent No. 89,098, dated April 20, 1869.

IMPROVEMENT IN CHURNS.

The Schedule referred to in these Letters Patent and making part of the same.

To all whom it may concern:

Be it known that I, GEORGE W. WARREN, of Alma, in the county of Alleghany, and State of New York, have invented a certain new and useful Improvement in Churns; and I do hereby declare that the following is a full and exact description thereof, reference being had to the accompanying drawings, making part of this specification, in which—

Figure 1 is a sectional elevation, and

Figure 2 a horizontal section of the barrel, with the dasher situated therein.

Like letters of reference indicate corresponding parts in both figures.

My improved churn belongs to that class where the churn body, or barrel is made to revolve around a stationary dasher inside, and where the moving power is a weight.

The invention consists in combining with the dasher-rod a vertically-acting key, which serves the double purpose of retaining the dasher against revolving and holding it to form the upper axis, or bearing of the revolving barrel.

It further consists in the arrangement of the mechanism as a whole.

In the drawings—

A indicates a suitable frame, in one end of which is mounted a revolving barrel, or churn body B, receiving motion by a train of gears, 1 2 3, mounted on shafts *a b*, acting on a cog-rim, 4, encircling the middle of the barrel.

A cord, *c*, winds on shaft *a*, and, passing over pulley *d*, has a weight, *f*, attached, which imparts the moving power.

A crank, *e*, enables the cord to be wound up at any time.

The barrel rests and turns at the bottom on a pointed step, *g*.

Inside it has a dasher, C, whose rod *h* passes up through the cover, and has a square, or equivalently-shaped socket *i*, into which strikes a vertically-acting key *k*, sliding in cross-bars *l l*.

This key, thus arranged, serves two special purposes—first, by striking into the socket *i*, it holds the dasher against turning while the barrel is revolved around it; and, second, when shut down it forms a stiff connection with the rod, and thus serves as the upper axis, or bearing around which the barrel moves.

I am aware that it is common in churns, where the barrel is stationary and the dasher revolves, to employ a key or other device simply to connect and disconnect the action of the dasher.

Such is not the equivalent of my arrangement, since but one purpose is served.

To produce the double action, as above described, requires a special arrangement of parts, viz: a vertically-acting key, in line with the dasher-rod, a short dasher-rod extending just through the cover and a square socket connection.

These features I believe original with myself.

This arrangement allows an easy connection and disconnection of the barrel, by simply moving the key up or down.

The general arrangement is simple and convenient. The central cog-rim around the barrel imparts an equal and uniform motion while the weight is wound up.

What I claim as my invention, and desire to secure by Letters Patent, is—

1. The combination, with the stationary dasher C and rotating-barrel B, of the vertically-sliding key *k*, the same being independent of the dasher, but preventing its rotation, and forming, with the dasher-shaft, the axis of the barrel, substantially as described.

2. The rotating-barrel B, having the operating and steadyng cog-rim 4, encircling its middle, in combination with the gearing 1 2 3, cord *c*, and weight *f*, when arranged and operating as described.

In witness whereof, I have hereunto signed my name, in the presence of two subscribing witnesses:

GEORGE W. WARREN.
